UNITED STATES PATENT OFFICE.

ALFRED L. WOODILL, OF RIVERSIDE, CALIFORNIA.

FRUIT-PACKING BOX.

No. 892,570.

Specification of Letters Patent.

Patented July 7, 1908.

Application filed December 15, 1906. Serial No. 347,972.

To all whom it may concern:

Be it known that I, ALFRED L. WOODILL, a citizen of the United States, residing at Riverside, in the county of Riverside and State 5 of California, have invented new and useful Improvements in Fruit-Packaging Boxes, of which the following is a specification.

The object of my invention is to produce a fruit packing box of light and durable mate- 10 rial which shall take up less room than the standard packing box now in use and which can be constructed at a less cost than the standard packing box. I accomplish this object by the packing box described herein 15 and illustrated in the accompanying drawings, in which:—

Figure 1.—is a perspective view of my improved packing box with a portion in one side broken away for clearness of illustration. Fig. 2.—is a longitudinal vertical section of my improved packing box on the line 2—2 of Fig. 1.

In constructing my improved packing box the main portion of the sides, the ends, the 25 top and the bottom are constructed of straw board or cardboard having perforations 3 therein for ventilation. The edges of the bottom 4 are turned upwardly to form attaching flanges 5, to which flanges the sides 30 and ends are secured in any suitable manner, preferably by sewing the same on a machine. V-shaped metallic corner strips 6 are secured at the meeting edges of the sides and ends. These corner strips are secured preferably by 35 stitching or stapling, and have the ends thereof turned inwardly beneath the bottom as best shown in Fig. 2, and the inturned ends are preferably secured together and to the bottom by rivets 7. At the top of the corner 40 strips on the side thereof which projects over the end there is an extension strip which is first bent outwardly and then parallel to the end piece and then inwardly and along the end to which it is secured, preferably by 45 rivets 8, which ears with the end form sockets 9, through which the longitudinal binder strips 10 pass downwardly therethrough and are then bent upwardly to lock them in place in the socket to hold the cover 11 in place on 50 the box. Like holding ears 12 are secured to the sides 13 to form sockets through which

the cross binder strips 14 pass downwardly and are then bent upwardly to lock them in place in the socket to assist in holding the cover in place on the box and also to prevent 55 the sides of the box from bulging outwardly when filled with fruit. Through the center of the box is the usual division strip 15, which is secured to the V-shaped metallic angle strips 16, which angle strips are also 60 secured to the side of the box. I prefer to have one of the angle strips extend from the top to the bottom as shown in Fig. 2, and the other angle strip on the other side of the partition to extend downwardly only a short 65 distance, as thereby I effect a saving in material, but if desired the short strip could be omitted altogether by packing in that end of the box first.

All of the metallic portions may be constructed of light material and by the use of cardboard in connection therewith a packing box is formed that possesses the requisite strength and at the same time is much lighter than the standard box and can be constructed 75 at less cost and takes up less space when packed in a car for shipping.

Having described my invention, what I claim is:

A fruit packing box composed of perforated card-board reinforced at the corners by metallic corner strips turned under and secured to the bottom; a card-board partition within said box between the ends thereof; metallic angle strips secured to each side of 80 said partition said strips being secured to opposite sides of said box respectively; metallic holding ears secured to the ends and sides of said box near the top thereof and longitudinal and transverse detachable flat 85 metallic binding strips passing over the cover of the box and around said holding ears, whereby the cover is secured upon the box.

In witness that I claim the foregoing I have 95 hereunto subscribed my name this 23rd day of November, 1906.

ALFRED L. WOODILL.
